INVENTOR:
W. O. Albert
Californian Co.

UNITED STATES PATENT OFFICE.

WILLIAM O. ALBERT, OF RACINE, WISCONSIN.

WAGON-BRAKE LEVER.

SPECIFICATION forming part of Letters Patent No. 240,069, dated April 12, 1881.

Application filed February 28, 1881. (Model.)

To all whom it may concern:

Be it known that I, W. O. ALBERT, of Racine, in the county of Racine and State of Wisconsin, have invented certain new and useful 5 Improvements in Wagon-Brake Levers; and I do hereby declare that the following is a full, clear, and exact description of the invention, which will enable others skilled in the art to which it appertains to make and use the same, 10 reference being had to the accompanying drawings, which form a part of this specification.

Figure 1 is a perspective view, and Fig 2 is a vertical sectional view taken through the brake-lever.

15 Similar letters of reference indicate corresponding parts in both figures.

This invention relates to wagon-brake levers; and it consists in certain improvements in the construction and arrangement of the same, 20 which will be hereinafter fully described, and particularly pointed out in the claim.

In the drawings hereto annexed, A represents the side of the wagon-body to which my invention is applied.

25 B is a curved bar or arc, secured to the wagon-box, as shown, and provided upon its side with teeth or ratchets C. At its ends the bar B is provided with outward-projecting standards or brackets D D, supporting a curved 30 plate, E, having a slot, F, of the same curvature as that of the arc B. The plate E may be provided at its ends with caps or supports G, and it may be independently secured to the side of the wagon-box by screws H, as shown.

35 A plate or bracket, I, projecting downwardly from one of the caps G, or from the ratchet-arc B, is provided with a bearing, J, for a lever, K, extending upward between the arc B and plate E, and provided with a tooth, L, 40 capable of engaging any one of the teeth or ratchets C. The lever K is provided with a laterally-extending pin or stud, M, sliding in the slot F, in plate E, between which and the body of the lever a coiled spring, N, is interposed upon the pin or stud M, for the purpose 45 of holding the lever in engagement with the ratchet-bar. A washer, O, may be adjusted

upon the pin M, outside the spring, for the purpose of preventing displacement of the latter, as shown.

50 At the point below the pin M the brake-lever K is provided with a rearward-extending pivoted rod, P, connecting the said lever with the brake in the usual well-known manner.

The operation of my invention will be readily understood from the foregoing description, 55 taken in connection with the drawings hereto annexed.

The brake-lever K is provided at its upper end with a handle, placed within convenient 60 reach of the driver, who, by throwing the lever forward, tightens the brake. The spring N at all times serves to force the brake-lever toward the ratchet-bar B, which is thus necessarily engaged to lock the brake. In order to 65 release the brake it is only necessary to move the lever K slightly outward against the tension of spring N, thus disengaging the tooth L from the teeth C and permitting the brake-lever to be drawn back.

70 This invention is simple and inexpensive, consisting of but few parts, and it is therefore easily operated and not liable to get out of order.

I am aware of Patents No. 124,941 and No. 75 190,458, and hence do not wish to be understood as claiming, broadly, the devices therein shown.

Having thus described my invention, I claim 80 and desire to secure by Letters Patent of the United States—

The combination, with the brake-lever carrying the pin M and spring N, of the curved ratchet-bar B, the curved slotted bar F, secured 85 by caps G and bolts H, and the arm I, forming a bearing for the lever, all constructed and arranged substantially as described.

In testimony that I claim the foregoing as my own I have hereunto affixed my signature in presence of two witnesses.

WILLIAM O. ALBERT.
